(57) CLAIM

The ornamental design for a shoulder-strap clip for a brassiere, as shown and described.

DESCRIPTION

FIG. 1 is a perspective view of a shoulder-strap clip for a brassiere, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is top plan view thereof;

FIG. 7 is a bottom plan view thereof; and,

FIG. 8 is a perspective view showing an embodiment of the claimed design, wherein the broken lines are shown for illustrative purposes only and form no part of the claimed design.
